OP D 17,630

UNITED STATES PATENT OFFICE.

JOSEPH KAUFMANN, NEW YORK, N. Y.

DESIGN FOR A CIGAR LIGHTER AND CUTTER STAND.

SPECIFICATION forming part of Design No. 17,630, dated August 16, 1887.

Application filed May 20, 1887. Serial No. 238,924. Term of patent 3½ years.

To all whom it may concern:

Be it known that I, JOSEPH KAUFMANN, of New York, in the county and State of New York, have invented and produced a new and original Design for a Cigar Lighter and Cutter Stand, of which the following is a specification, reference being had to the accompanying photograph, forming part thereof.

The leading features of my design are conventional representations of the column or post, lantern, burner, and letter-box of street lamp-posts and letter-boxes; also, in connection therewith, representations of posts and chains placed around the lamp-post and letter-box.

15 In the photographic illustration, A is the column or post, which represents the lamp-post; b, the burner; B, the lantern; C, the cutter, representing a letter-box having a central hole, d; D, the base of the lamp-post; F, F, &c., the posts; f, chains, and G the caps of the posts.

I claim—

1. The design for a cigar lighter and cutter stand herein described and shown, the same comprising a conventional representation of a 25 street lamp-post and letter-box, and composed of the post A, burner b, lantern B, and letter-box C, having central opening, d.

2. The design for a cigar lighter and cutter stand herein described and shown, the same 30 being a conventional representation of a lamp-post and letter-box, and consisting of the post A, lantern B, cutter-box C, having central opening, d, base D, posts F, and chains f, and caps G.

In testimony that I claim the foregoing as my invention I have hereunto subscribed my name this 17th day of May, 1887.

JOSEPH KAUFMANN.

In presence of—

JOHN T. FPNLON,
MILTON C. DONN.
